UNITED STATES PATENT OFFICE

LEO W. MANION, OF CANTON, OHIO, ASSIGNOR, BY MESNE ASSIGNMENTS, TO FERRO ENAMEL CORPORATION, OF CLEVELAND, OHIO, A CORPORATION OF OHIO

FURNACE

Application filed May 20, 1929. Serial No. 364,477.

This invention relates to furnaces and more particularly to a U or hairpin type furnace which is adapted for such use as burning enamel ware.

5 It is among the objects of my invention to provide a furnace through which such articles as enamel ware are continually moved; wherein the burning chamber of the furnace has but one opening and through 10 which an uninterrupted stream of incoming and outgoing ware may pass; wherein the furnace also comprises a preheating and cooling chamber adjacent the burning chamber in which oppositely moving streams of 15 burned and unburned ware move in opposite directions and in close proximity so that burned ware delivers heat to unburned ware. Another object is to provide a continuous 20 furnace of the U or hairpin type, in which ware is moved in a burning chamber and carried through an arc of 180° and then moved out of the burning chamber. Another object is 25 to direct the path of the products of combustion away from the burning chamber adjacent the unburned ware to preheat the unburned ware.

Other objects include providing a furnace having a closed end wherein circulation of air is reduced to a minimum thereby 30 conserving heat. A further object is to conserve heat by providing shoe plates and other means for a continuous sliding cover for the slotted opening through which the ware supporting parts extend. Other objects include 35 supporting the ware on points and convenient carriers which facilitate burning and handling. A still further object is to provide pivotal connections in the ware carrying mechanism which will permit the ware to be 40 continuously supported on upwardly directed supports and while permitting angular movement between various parts of the carrying mechanism.

Other objects will appear from the following description of a preferred form of my invention, reference being had to the accompanying drawings. The essential characteristics are summarized in the claims.

In the drawings, Fig. 1 is a side elevation 50 of my furnace along with ware conveying

mechanism; Fig. 2 is a horizontal section taken along the lines 2—2 of Fig. 1; Fig. 3 is a vertical section taken along the lines 3—3 of Fig. 2; Fig. 4 is a front elevation of the furnace; Figs. 5 and 6 are vertical sections taken along the lines 5—5 and 6—6 respectively of Fig. 2; Fig. 7 is an enlarged side elevation taken at the front of the furnace showing the conveying structure and shoe plate guides; and Fig. 8 is a perspective of one of the shoe plates.

Referring to the drawings, I show a furnace 1 which may be constructed of suitable materials such as fire brick and the like according to well known precepts. The furnace comprises essentially a burning chamber 2 and a preheating and cooling chamber 3. Suitable ports or doors 4 and 5, being only large enough to receive ware with appropriate carriage, are provided at the front end of 70 the furnace, the back end of the furnace being closed.

A conveying system is illustrated for carrying the ware into and out of the furnace and comprises essentially a continuous, suitably supported, trackway 10 carrying trolleys 11 from which are suspended ware carrying and transporting means. The conveying system also comprises an endless chain 12 of which certain links, see Fig. 7, are pivotally suspended from the trolleys and in turn pivotally support trunnions 13 by which the ware is moved into and out of the furnace.

The trunnions are engaged in split bearings 14 which in turn pivotally support hanger rods 15 through pins 16 whereby a swinging movement is permitted between the trunnions and the hanger rods. The lower ends of the rods 15 have eyes 17 for pivotally receiving work engaging tools 18, see Figs. 1 and 4, or work carrying trays 19 as shown in Figs. 3 and 5. The tools 18 have pointed ends for directly supporting certain shapes of ware, and the trays 19 have point supports for such articles as pots and pans as shown. In either event, the pivotal connection between the trolleys, links, trunnions, rods and tools permit various parts to be angularly displaced while the tools and trays keep a constant position relative to the ware. Thereby 100

the pointed supports which engage the ware always extend vertically regardless of the angular deviation of the other parts from the vertical.

- 5 Carried and supported by collars 20 on the hanger rods is a continuous articulated shield 21 which comprises shoe plates, see Fig. 8, slidably engaging tracks 23 on the top of the furnace. The shoe plates 22 are stepped an 10 amount substantially equal to their thickness and have round holes in their forward ends engaging hanger rods by which they are drawn, and have elongated holes in their rearward ends to facilitate their turning. 15 The track 23 comprises a pair of angle bars which overhang the front of the furnace and are declined to slidably receive the shoe plates. The bars constituting the track lie on opposite sides of a continuous U-shaped 20 slot 24 through which the rods 15 extend and progress through the furnace.

The chain 12 passes over horizontally disposed sprocket wheels at opposite ends of its travel located at the extreme left and right 25 of Fig. 1. At least one of these sprocket wheels is driven by suitable means, not shown, thereby moving the ware through the furnace. The ware is loaded and unloaded at the front end of the furnace near the doors 30 4 and 5, the unburned ware entering through the door 5 and progressing through the pre-heating and cooling chamber to the burning chamber, whence it is carried through an arc of 180° and returned through the preheating 35 and cooling chamber out of the door 4 where it is unloaded.

The foregoing has described my furnace in a general way and has particularly dealt 40 with the means and manner in which the ware or other material is conveyed through the furnace. The following will describe the furnace proper in greater detail and while I have illustrated the furnace operable with fluid or gaseous fuel, I wish it to be understood 45 that the precepts of my invention are broad enough to include various kinds of fuel, whether combustible or otherwise. The furnace illustrated herein is adapted to burn fuel oil, but I have designed and successfully 50 operated furnaces of this same type with electricity as the means for heating, and I contemplate that solid fuels, such as coal, could be successfully used with the addition of suitable grates and other ancillary equipment.

Referring to Figs. 2, 3 and 6, and illustrating a fluid fuel heating system, I provide 55 a plurality of burners 29 which are directed alternately and oppositely under the floor 60 of the burning chamber 2. The burners project into combustion chambers 30, the tops of which are covered with high refractory material preferably laid as inverted V's to give a maximum surface for radiation and 65 conduction. The ends of the chambers 30

opposite the burners communicate freely with chambers 31 which constitute the side walls of the burning chamber and are interiorly lined with high refractory material through which heat is transmitted to the 70 ware. Thus the flame and products of combustion from the burners pass under the floor of the burning chamber and along the side walls, out of contact with the ware which moves through the chamber.

Those skilled in the art will appreciate that the refractory lining of the bottom and sides of the burning is, in fact, the part from which heat emanates and flows to the ware, and if electrical heating elements were similarly 80 disposed, the effect within the burning chamber would be substantially the same. The selection of the heating means may hinge upon the cost of power and fuel in various localities. One of the advantages in using 85 a combustible fuel is that the products of combustion may be used after they leave the vicinity of the burning chamber to preheat the ware during its inward passage through the preheating and cooling chamber.

Communicating with the upper portions 90 of the chambers 31, I provide exhaust openings 32 and 33 through which the products of combustion pass downwardly and then laterally partly through the passage 34 and into 95 a longitudinally extending passage 35 (see Figs. 2 and 5) which extends under the floor of the side of the preheating and cooling chamber over which the incoming ware passes. The passage 35 may conveniently 100 terminate in a stack 36 adjacent the door of the furnace.

As indicated above, the incoming ware enters the port or door 5 and is carried along above the passage 35 and laterally adjacent 105 the hot burned ware which leaves the furnace by the door 4. The incoming ware is thus preheated both by its proximity to the products of combustion and also by its proximity to the burned ware. The unburned 110 ware thus has its temperature gradually raised by the heat which might otherwise be wasted and obtains a high degree of preheat before entering the burning chamber proper. Within the burning chamber the ware is 115 passed adjacent one of the side walls and turned around and moved back adjacent the other side wall and out of the burning chamber into the preheating and cooling chamber.

The ware is of course completely burned in the burning chamber and it is my intention 120 that after leaving the burning chamber it deliver up its heat to the incoming and unburned ware. Preferably the preheating and 125 cooling chamber is about twice as long as the burning chamber, although variations in the relative lengths of the chambers may be found advisable according to the character of the duty imposed upon the furnace. Gen- 130

erally stated, I prefer that the length of the preheating and cooling chamber be relatively increased in proportion to the mass or specific heat of the ware.

5 While the foregoing illustrates and describes a preferred form of my invention, modifications will occur to those skilled in the art and I do not care to be limited in the scope of my patent other than by the claims 10 appended hereto.

I claim:-

1. The combination with a U-type furnace of a continuous conveyor for carrying articles through said furnace comprising a guide rail located outside of the furnace, a plurality of hangers spaced upon said rail, a chain interconnecting said hangers, supporting members pivotally mounted upon said hangers, said furnace having a roof provided with a 15 continuous U-shaped opening for receiving said supporting members, and means for preventing the escape of heat through said continuous opening, said last named means comprising overlapping plates engaged by 20 said supporting members and slidable along the furnace roof, said plates being solely supported by said roof while over the furnace and by said supporting members when away 25 from the furnace.

30 2. A furnace comprising a preheating and cooling chamber, a burning chamber located at one end of said preheating and cooling chamber, means substantially covering the walls and floor of said burning chamber 35 whence heat emanates into said chamber, means for conveying articles through said preheating and cooling chamber and said burning chamber whereby said articles are conveyed into and from said preheating and 40 cooling chamber in substantially parallel adjacent paths comprising a guide rail located outside of said furnace, a plurality of hangers spaced upon said rail, a chain interconnecting said hangers, supporting members 45 pivotally mounted upon said hangers, said furnace being provided with a continuous U-shaped opening for receiving said supporting members, and covering members for preventing the escape of heat through said 50 continuous opening, said covering members including overlapping plates engaged by said supporting members and slidable along the furnace roof, said plates being solely supported by the furnace roof while over said 55 continuous opening and by said supporting members while away from said continuous opening.

3. A U type furnace having a burning chamber heated by combustible fuel, a pre-heating and cooling chamber through which burned and unburned ware are conveyed in close proximity in opposite directions whereby the unburned ware is preheated by the burned ware, and means for conducting the 60 products of combustion through the preheat-

ing chamber out of contact with the ware and proximate the unburned ware.

4. An enameling furnace having a closed end and an open end, a burning chamber at the closed end adjacent which combustible fuel is burned, a preheating chamber extending from the open end to the burning chamber, and means for conducting the products of combustion from the burning chamber substantially to the open end of the furnace for 70 heating the said preheating chamber.

5. The method of burning ware which consists in conveying a continuously moving stream of ware through an enclosed chamber, turning the stream of ware through an arc of 180°, burning a combustible fuel at or near the point of turning and directing the heat therefrom onto the ware at that point to burn it, conveying the ware from the point of turning back in a direction opposite to the movement of the unburned ware and in close proximity thereto, whereby heat flows from the burned to the unburned ware to preheat it and causing the products of combustion to flow in a path parallel the path of the unburned ware and in a direction opposite to the movement thereof and proximate thereto for preheating the unburned ware.

6. A furnace comprising a preheating and cooling chamber, a burning chamber located at one end of said preheating and cooling chamber, means for heating said burning chamber, means for conveying articles through said preheating and cooling chamber and said burning chamber whereby said articles are conveyed into and from said preheating and cooling chamber in substantially parallel adjacent paths, said conveying means comprising a guide rail located outside of said furnace, a plurality of downwardly extending work supporting members spaced upon said guide rail, flexible connecting means interconnecting said supporting members, said furnace being provided with a continuous U-shaped opening for receiving said supporting members, and covering members for preventing the escape of heat through said continuous opening, said covering members including overlapping plates engaged by said supporting members and slidable along the furnace roof, said supporting plates being wholly supported by the furnace roof while over said continuous opening and by said supporting members while away from said continuous opening.

7. The combination with a U-type furnace of a continuous conveyor for carrying articles through said furnace comprising a guide rail located outside of the furnace, a plurality of downwardly extending work supporting members spaced upon said rail, flexible connecting means interconnecting said supporting members, said furnace having a roof provided with a continuous U-shaped opening for receiving said supporting members, and
